UNITED STATES PATENT OFFICE.

CYRUS HOWARD HAPGOOD, OF NUTLEY, AND GEORGE F. MAYNO, OF EAST ORANGE, NEW JERSEY, ASSIGNEES TO THE DE LAVAL SEPARATOR COMPANY, OF NEW YORK, N. Y., A CORPORATION OF NEW JERSEY.

PROCESS OF REFINING VEGETABLE OILS.

Application filed February 6, 1924. Serial No. 690,904.

To all whom it may concern:

Be it known that we, CYRUS HOWARD HAPGOOD and GEORGE F. MAYNO, citizens of the United States, residing at Nutley and East Orange, respectively, county of Essex, State of New Jersey, have invented a new and useful Improvement in Processes of Refining Vegetable Oils, of which the following is a full, clear, and exact description, reference being had to the accompanying drawings, which form a part of this specification.

In a patent issued to us May 29, 1923, No. 1,457,072, is set forth a process of refining vegetable oils in which a stream of a saponifying agent flows into contact with a stream of oil, the oil and saponifying agent being mechanically mixed during the flow to only the degree required to effect a primary saponification of the fatty acids without saponification of a substantial proportion of the free oil. Immediately thereafter the flowing mixture of oil and soap was admitted to a centrifugal separator, wherein the constituents were admixed for a relatively short time, effecting a secondary saponification of fatty acids followed by centrifugal separation and separate discharge of oil and soap. Thereafter the oil was treated with an inert clarifying agent.

Our present object is to provide a process intended for the same purpose and which, although embodying certain of the patented features, is an improvement on the patented process. Special objects are: to maintain as short as possible the time required for agitation of the oil and saponifying agent and yet effect complete saponification of the fatty acids while avoiding saponification of any part of the oil itself; to make it feasible to use, as nearly as possible, just the amount of saponifying agent required to saponify the fatty acid and little or no more; to effect a more thorough decolorization of the oil; to reduce the refining loss; and to produce a soap stock of enhanced value.

In processes heretofore in use, the action of the caustic soda or other saponifying agent on the oil has been uncertain on account of the varying nature of the gums, resins, albumens and other similar bodies present in the crude oil. The caustic soda must remove these materials as well as the fatty acids. It has been necessary, therefore, to use an excessive amount of caustic

soda. In our patented process the excess amount of caustic soda is reduced and by reason of the continuity of the process and other features hereinbefore recited, more satisfactory products have been obtained, but still with substantial room for improvement in regard to the several objects, hereinbefore recited, of the present invention.

The objects of the present invention are secured by retaining certain features of the patented process but with important modifications, such as the elimination from the oil of the albumens, resins and gums before admixture with the oil of the caustic soda, so that the only function left to the caustic soda to perform is the neutralization of the fatty acids. Limited to this function, it is only necessary to ascertain the percentage of fatty acid present in the oil and adjust the strength of lye to conform thereto. Thereby, the oil is separated out without substantial loss, and it is of excellent color and substantially free from fatty acid; while a soap stock, nearly water white, and of enhanced value, can be recovered.

The process is applicable to the purification of all vegetable oils; for example, cotton oil, corn oil, soya bean oil, peanut oil.

The execution of the process is not dependent on the employment of any particular apparatus, and indeed, in the apparatus that we preferably employ, no novelty resides in any of the separate instrumentalities of the apparatus, although they are associated together in a new relation. It is, therefore, unnecessary to illustrate the apparatus in detail, the drawing being a diagram of the apparatus that we prefer to use.

The crude oil is pumped into a large agitating scale tank *a*, wherein it is heated to a temperature of from 120° to 220° F., preferably at about the highest temperature in this range. The oil continuously runs by gravity into a mixer, such as a centrifugal mill *b*.

The tank *c* contains an inert clarifying and bleaching agent, such as fuller's earth, "filro", silica gel (silicate of soda treated with hydrochloric acid), a suitable diatomaceous earth, etc. While a clarifying and bleaching agent of maximum efficiency is highly desirable, the use of any particular agent, so long as it is efficient, is not necessary. We prefer "filro", which is a well

- known and readily procurable, commercial clarifying and decolorizing agent compounded by a secret process and whose chemical composition or method of preparation we cannot with certainty specify. The clarifying and bleaching agent is admixed with sufficient of the oil to be refined to allow it to continuously flow freely by gravity to the mixer *b*.
- 10 In this mixer the ingredients are thoroughly agitated and continuously discharge into a pipe *d* leading to a weir tank *e*, through which, also, there is a continuous flow. This tank may be a closed receptacle provided with pairs of partitions *f* and *g*, forming a series of compartments *h*. Some of the clarifying and bleaching agent settles in the first compartment *h*; the oil, with the remainder of such agent, flowing over the first plate *f* as a weir and down between such plate and adjacent plate *g* into the second compartment *h*. Herein, as well as in the third compartment *h*, there is a further partial separation and settlement; the oil discharging into the pipe *i* being largely freed of the clarifying and bleaching agent, which has almost completely removed the gums, resins, albumens and color bodies generally, present in the original oil.
- 30 The decolorized oil discharges into a centrifugal clarifier *j* (which is, preferably, a centrifuge with but one outlet), wherein all suspended matter, including the clarifying and bleaching agent, is removed. The thus cleaned oil discharged from the clarifier passes through a pipe *k* which extends through a temperature changer *m*, which cools the oil to (say) from 80° to 120° F. Into the flowing stream of cooled oil is discharged caustic soda, or another suitable saponifying agent, which continuously flows into pipe *k* from a tank *n*. It is possible to quite accurately predetermine the rate of flow of the caustic soda relative to the rate of flow of oil, so as to mix with the oil just the quantity of caustic soda needed to saponify the fatty acids of the oil and practically no more. It is advisable to run the flowing mixture through a mechanical mixer *o* (which may be similar to mixer *b*) in order to insure an intimate contact between the fatty acids and the saponifying agent; but the time of admixture need be relatively short to produce the "break" required for settlement of the soap stock. The mixture or emulsion then discharges into a centrifugal separator *p*, wherein there is a measurable secondary saponification. In the separator, oil is separated from the soap.
- 50 The oil is pumped to any desired place, such as special process plants, filtering plants, etc. The soap stock is pumped to storage or to acidulating tanks.
- 60 The process, it will be noted, is a continuous one. It may be operated, if desired, for

twenty-four hours or more. The mechanism may then be washed out with a small quantity of hot water without stopping the process or removing any of the tinware.

The resultant yellow or refined oil is neutral, free from fatty acid, soap, insoluble impurities and moisture. No measurable quantity of oil is retained by the clarifying and bleaching agent or carried out with the soap, thus avoiding a refining loss which, in ordinary processes, is quite serious.

In the practice of the process, it is preferable that the whole apparatus shall be closed to the atmosphere.

Having now fully described our invention, what we claim and desire to protect by Letters Patent is:

1. A continuous process for refining vegetable oils which comprises heating the oil and subjecting it to the action of a clarifying and bleaching agent, removing said agent together with the impurities carried off thereby, then mixing the decolorized oil, still containing its fatty acids but otherwise purified, with a saponifying agent in proportions adapted to effect a maximum saponification of fatty acids and a minimum saponification of oil, and separating the oil and soaps.

2. A continuous process for refining vegetable oils which comprises flowing a stream of a clarifying and bleaching agent into contact with a flowing stream of heated oil and subjecting the flowing mixture to a mixing action, then separating the oil from the filtering and bleaching agent and the impurities carried off thereby, then flowing the oil into contact with a flowing stream of a saponifying agent and subjecting the same to a mixing action the proportion of the saponifying agent added being such as to effect saponification of the fatty acids without substantial saponification of the oil, and subjecting the flowing stream of oil and soaps to centrifugal force to effect their separation.

3. A continuous process for refining vegetable oils which comprises flowing a stream of a clarifying and bleaching agent into contact with a flowing stream of heated oil and subjecting the flowing mixture to a mixing action, then separating the oil from the filtering and bleaching agent and the impurities carried off thereby, then cooling the oil and flowing it into contact with a flowing stream of a saponifying agent and subjecting the same to a mixing action, the proportion of the saponifying agent added being such as to effect saponification of the fatty acids without substantial saponification of the oil, and subjecting the flowing stream of oil and soaps to centrifugal force to effect their separation.

4. A continuous process for refining vegetable oils which comprises flowing a stream

- of a clarifying and bleaching agent into contact with a flowing stream of heated oil, subjecting the flowing mixture to a mixing action and then to gravity settlement to remove the larger part of said agent and of the color bodies in the original oil, subjecting the thus largely purified oil to centrifugal force to effect a substantially complete removal of suspended matter, flowing it into contact with a flowing stream of a saponifying agent and subjecting the same to a mixing action the proportion of the saponifying agent added being such as to effect saponification of substantially all the fatty acids without substantial saponification of the oil, and subjecting the flowing stream of oil and soaps to centrifugal force to effect their separation.
5. A continuous process for refining vegetable oils which comprises flowing a stream of a clarifying and bleaching agent into contact with a flowing stream of heated oil, subjecting the flowing mixture to a mixing action and then to gravity settlement to
- remove the larger part of said agent and of the color bodies in the original oil, subjecting the thus largely purified oil to centrifugal force to effect a substantially complete removal of suspended matter, cooling the oil and flowing it into contact with a flowing stream of a saponifying agent and subjecting the same to a mixing action the proportion of the saponifying agent added being such as to effect saponification of substantially all the fatty acids without substantial saponification of the oil, and subjecting the flowing stream of oil and soaps to centrifugal force to effect their separation.
10. In testimony of which invention, I, CYRUS HOWARD HAPGOOD, have hereunto set my hand at New York city, New York, on this 1st day of February, 1924, and I, GEORGE F. MAYNO, have hereunto set my hand at New York city, New York, on this 1st day of February, 1924.
15. CYRUS HOWARD HAPGOOD.
GEORGE FREEBORN MAYNO.
